DESIGN FOR A SHOE

Ruth V. Lee, New York, N. Y.

Application June 20, 1942, Serial No. 107,274

Term of patent 3½ years

To all whom it may concern:

Be it known that I, Ruth V. Lee, a citizen of the United States of America, residing in New York, county of New York and State of New York, have invented a new, original, and ornamental Design for a Shoe, of which the following is a specification, reference being had to the accompanying drawing, forming part thereof.

The figure on the drawing is a front perspective view of a shoe showing my new design. The opposite side presents substantially the same appearance as the side shown.

I claim:

The ornamental design for a shoe, substantially as shown and described.

RUTH V. LEE.
